DELAWARE.

SOOT-BLOWER HEADER.

Specification of Letters Patent.

Patented May 27, 1919.

1,304,609.

Application filed October 23, 1917. Serial No. 198,013.

To all whom it may concern:

Be it known that I, WILLIAM F. SELLERS, a citizen of the United States of America, and a resident of Brandywine Hundred, 5 Delaware, have invented a certain new and useful Improvement in Soot-Blower Headers, of which the following is a true and exact description, reference being had to the accompanying drawings, which form a part 10 thereof.

My present invention consists of novel means for connecting metallic pipes to metal tubes for use where both the pipes and the tubes are subjected to high temperatures, 15 and the tubes do and the pipes do not contain at all times, a heat absorbing liquid. The primary object of the invention is to provide an effective heat conducting connection between the said pipes and tubes where- 20 by the heat absorbing effect of the liquid in the tubes operates to keep the pipes from reaching undesirably high temperatures. My invention is especially devised and adapted for use as a means for protecting the 25 soot blower pipes located in the furnace chamber of a water tube boiler against the temperatures to which they are subjected by connecting them in good heat conducting relation with the water tubes of the boiler.

30 The various features of novelty which characterize my invention are pointed out with particularity in the claims annexed hereto and forming a part of this specification. For a better understanding of the invention, 35 however, and the advantages possessed by it, reference should be had to the accompanying drawings and descriptive matter in which I have illustrated and described a preferred embodiment of my invention.

40 Of the drawings:

Figure 1 is a sectional elevation of a portion of the water tube boiler.

Fig. 2 is a partial section on the line 2—2 of Fig. 1.

45 Fig. 3 is an elevation with parts broken away and in section of the apparatus shown in Fig. 2; and

Fig. 4 is a perspective view of a connect- 50 ing part.

55 In the drawings A represents the tubes of a water tube boiler of conventional form, and B and B' represent baffles transverse to the water tubes. C represents blower pipes having upper portions embedded in the baf- fles B and B', and arranged to discharge

jets of a cleaning fluid as air or steam into the inter tube space, ordinarily in directions parallel to the length of the tubes. The blower pipes C' in each baffle are connected at their lower ends to a header or supply 60 main pipe C, which is located beneath the lower row of water tubes and extends transversely to the latter, and directly across the path of the products of combustion.

The pipes C are connected to the water 65 tubes A above them by metallic clamps D, and are placed in good heat conducting relation with the tubes A by means of the clamps and metallic saddle blocks or spacers F interposed between each pipe C and some 70 or all of the tubes A in the lower row of the boiler water tubes. As shown, each clamp D comprises two opposed similar parts d. Each part d comprises a body portion extending between an adjacent pair of 75 tubes A and is provided at its upper end with oppositely projecting horns or arms D' which extend over the two tubes between which the body portion of the clamping part extends. At its lower end each clamping 80 part d is formed with a curved seat D² shaped to fit against the adjacent side of the pipe C. Each clamping part is also formed between the ends with a lug or shoulder D³. The two clamping parts of each 85 clamp are secured together by means of a clamping bolt E which passes between the upper side of the pipe C and the line of contact between the opposing shoulders D³ of the two clamping parts d. Each saddle 90 block or spacing part F, in the preferred construction illustrated, is formed with a cylindrical seat F' in its upper side shaped to fit against the under side of the correspond- 95 ing water tube A, and is formed at its under side with a cylindrical seat F² transverse to the seat F' and shaped to receive the upper side of the corresponding soot blower pipe C.

With the construction described and with 100 the parts assembled as shown in the drawing the tightening up of the bolt E of each clamp causes each of the clamping parts d connected thereby to fulcrum about the line of contact between the opposing shoulders D³ as an axis and thereby grip the corre- 105 sponding pipe C between the opposing seats D² of the clamp. These seats are so shaped and the parts are so proportioned that the gripping action of the seats tends to cam or 110

- lift the pipe C upward and thus put the saddle blocks F between the tubes A and pipes C under compression. The contact surfaces of the saddle blocks and the pipes C and tubes A, and of the clamps D and the tubes A and pipes C are made relatively large so that the pipes C are thus not only well secured mechanically to the water tubes but are in good heat transferring relation with the latter. The pipes C, as well as the saddle blocks F and the clamps D are therefore maintained at a temperature practically no higher than that of the water in the water tubes A, although the temperature of the products of combustion sweeping over the pipes C and clamps D is much higher. By the use of my invention a serious practical difficulty heretofore experienced with boiler soot blower arrangements of the general character illustrated is avoided. The soot blower pipes C' proper may be sufficiently protected against the temperature to which they are subjected by embedding their upper portions in the baffle walls and by covering the lower portions of these pipes with a suitable refractory heat insulating covering G, but it has not been found practically possible to satisfactorily protect the main or header pipes C by such a covering.
- 30 While in accordance with the provisions of the statutes I have illustrated and described the best form of my invention now known to me, it will be apparent to those skilled in the art that changes may be made 35 in the form of my invention without departing from its spirit, and that some features of my invention may sometimes be used to advantage without a corresponding use of other features of the invention.
- 40 Having now described my invention, what I claim as new and desire to secure by Letters Patent, is:
1. In a water tube boiler, the combination with the water tubes, of a pipe or header and metallic spacers and clamps having extended surfaces in contact with both the water tubes and header.
  2. In a water tube boiler, the combination with the water tubes, of a pipe or header, metallic spacers or saddle blocks interposed between the pipe or header and the water tubes and having extended cylindrical segment surfaces in contact with both the headers and tubes, and clamps holding the tubes and headers against the interposed saddle blocks.
  3. In a water tube boiler, the combination

with the water tubes, of blower piping and metallic parts connecting, and having extended contact surfaces in gripping contact 60 with said tubes and pipe.

4. In a water tube boiler the combination with the water tubes of a blower pipe or header extending transversely of the bank of tubes, metallic saddle blocks interspaced 65 between the pipes and adjacent tubes and each formed with a cylindrical seat for the pipe and with a transverse cylindrical seat for the adjacent water tube, and metallic clamping means extending between the pipe 70 and adjacent water tubes and serving to clamp the pipe and water tubes in the corresponding saddle block seats.

5. In a water tube boiler the combination with the water tubes of a blower pipe or 75 header extending transversely of the water tubes, and clamps for connecting the pipe to adjacent water tubes, each clamp comprising coöperating parts each of which has a portion extending between the adjacent pair 80 of water tubes with projections at one end of said portion adapted to engage the said pair of tubes, and provided at its opposite end with a surface adapted to engage the pipe and provided between its ends with a shoulder adapted to abut against the corresponding shoulder of the coöperating clamping part, and clamping means acting on the coöperating clamp parts and tending to draw the pipe engaging surfaces of the latter together, said surfaces being shaped to force 85 the pipe toward the tubes as the surfaces approach one another.

6. In a water tube boiler the combination with the water tubes of a blower pipe or 90 header extending transversely of the water tubes, and clamps for connecting the pipe to adjacent water tubes, each clamp comprising coöperating parts each of which has a portion extending between the adjacent 100 pair of water tubes with projections at one end of said portion adapted to engage the said pair of tubes, and provided at its opposite end with a surface adapted to engage the pipe and provided between its ends with a shoulder adapted to abut against the corresponding shoulder of the coöperating 105 clamping part and a clamping bolt for drawing the coöperating clamp parts together passing between the pipe and the said 110 shoulders; the said surfaces being shaped to force the pipe toward the tubes when said clamping bolt is tightened.

WM. F. SELLERS.
